C. METZ-METZETTI

RADIOCABINET

Filed Dec. 5, 1924

Charlie Metz-Metzetti Inventor

By his Attorney George C. Heinrich

Patented Apr. 7, 1925.

Des. 66,979

UNITED STATES PATENT OFFICE.

CHARLIE METZ-METZETTI, OF NEW YORK, N. Y.

DESIGN FOR A RADIOCABINET.

Application filed December 5, 1924. Serial No. 11,594. Term of patent 3½ years.

To all whom it may concern:

Be it known that I, CHARLIE METZ-METZETTI, a citizen of the United States, residing at New York, in the county of New York and State of New York, have invented a new, original, and ornamental Design for Radiocabinet, of which the following is a specification, reference being had to

the accompanying drawing, forming part thereof.

The figure is a plan view of a radiocabinet, showing my new design.

I claim:

The ornamental design of a radiocabinet, as shown.

CHARLIE METZ-METZETTI.
